ROTATABLE AND TRANSLATABLE DRAWING BOARD

Leslie Royce Huff, 266 Mill St., Westwood, N.J.; Hazel Shuman Huff, administratrix of the estate of Leslie Royce Huff, deceased

Filed Dec. 15, 1961, Ser. No. 159,581
9 Claims. (Cl. 45—131)

This invention relates to rotatable and translatable drawing boards. The present invention is an improvement over that in my prior Patent No. 2,894,355, entitled "Endless Paper Roll Type Drafting Board," issued on July 14, 1959. In that prior patent there are shown two arrangements of drawing boards rotatable about a horizontal axis, two arrangements of drawing boards that are translatable and three arrangements in which the drawing paper is slideable over the drawing board.

The object of the present invention is to provide a drawing board which is rotatable about a horizontal axis and maintained in any desirable position by means of adjustable clutches and also translatable to enable the draftsman to reach a large area of the drawing board, while seated in an ordinary chair.

Another object of the present invention is to provide a drawing board on which the drawing paper is trained over a pair of winding rollers and a tension roller to provide for moving the drawing paper across the drawing board.

A further object of the present invention is to provide a drawing board with an arrangement of winding and tension rollers for moving the drawing paper across the board and in which the rollers are positioned within easy reach of the draftsman for right or left handed operation.

An additional object of the present invention is to provide a drawing board supported on a slideable carriage having an arrangement of winding and tension rollers for moving the paper across the board, in which the rollers are removable from the carriage and can be relocated or placed in storage, either empty or with paper on same.

Still another object of the present invention is to provide a drawing board supported on a slideable carriage having an arrangement of winding and tension rollers for moving the paper across the drawing board in combination with an elevating means for holding the carriage and drawing board in a selected elevated position.

An additional object is the provision of an elevating means for holding the carriage and drawing board in a selected elevated position the carriage with the drawing board being rotatable around a vertical axis to the drawing board.

Still other objects, advantages and improvements will become apparent from the following specification, taken in connection with the accompanying drawings, in which:

FIGURE 1 is a top plan view of a desk mounting a drawing board in accordance with the present invention, with the desk broken away on the opposite sides of the drawing board to show the locations of the winding and tension rollers;

FIGURE 2 is a transverse sectional view, taken on the section line 2—2 of FIGURE 1 and looking in the direction of the arrows, showing the releasable mountings for the winding rollers and the adjusting means for the tension roller;

FIGURE 3 is a vertical sectional view, similar to FIGURE 2, showing the carriage which supports the drawing board shifted forwardly so as to be free of the rear section of the desk and in a position to be revolved around its transverse horizontal axis;

FIGURE 4 is an end elevational view, showing the clutch housings on the opposite sides of the carriage which

2

supports the drawing board and the guides in which the latter travel;

FIGURE 5 is a partial sectional view, taken on the section line 5—5 of FIGURE 2 and looking in the direction of the arrows, showing the rotatable mounting of the tension roller;

FIGURE 6 is a vertical sectional view through one of the cone clutches at the opposite ends of the horizontal shaft, which slidably mounts the carriage supporting the drawing board, taken substantially along the line 6—6 of FIGURE 1 as viewed in the direction indicated by the arrows;

FIGURE 7 is a detail vertical sectional view, taken on the line 7—7 of FIGURE 3 and looking in the direction of the arrows, showing two of the quadruple needle bearings, which rotatably support the cone clutches in the guide plates;

FIGURE 8 is a detail vertical sectional view, taken on the section line 8—8 of FIGURE 2 and looking in the direction of the arrows, showing the rotatable mounting of one of the winding rollers;

FIGURE 9 is a detail horizontal sectional view, taken on the section line 9—9 of FIGURE 2 and looking in the direction of the arrows, showing one of the arms for releasably holding the winding rollers in place;

FIGURE 10 is a top plan view showing the two parallel screws for moving the carriage which supports the drawing board outwardly toward the rear of the desk;

FIGURE 11 is a transverse sectional view, taken on the section line 11—11 of FIGURE 10 and looking in the direction of the arrows, showing one of the parallel screws for moving the carriage which supports the drawing board;

FIGURE 12 is a detail longitudinal sectional view, taken on the section line 12—12 of FIGURE 10 and looking in the direction of the arrows, showing the clutch shaft housing and one of the slideable blocks, which are moved by the parallel screws;

FIGURE 13 is a detail transverse sectional view, taken on the section line 13—13 of FIGURE 10 and looking in the direction of the arrows, showing a modification of the needle roller bearings, which mount the clutch housings for linear movement in the transversely positioned guides;

FIGURE 14 is a detail transverse sectional view, taken on the section line 14—14 of FIGURE 10 and looking in the direction of the arrows, showing one of the rear mountings, which rotatably support the parallel screws;

FIGURE 15 is a detail transverse vertical sectional view, taken on the section line 15—15 of FIGURE 10 and looking in the direction of the arrows, showing one of the front mountings which rotatably support the parallel screws;

FIGURE 16 is a top plan view showing a modification in which the carriage supporting the drawing board is mounted for movement transversely of the desk by a slide, which is secured to the carriage, and a guide, which is secured to the desk;

FIGURE 17 is a top plan view, similar to FIGURE 16, showing a square drawing board and slides on the opposite sides of the carriage supporting same, which slides cooperate with guides secured to the desk;

FIGURE 18 is a transverse vertical sectional view, taken on the section line 18—18 of FIGURE 16 and looking in the direction of the arrows, showing a latching device for holding the carriage supporting the drawing board in any one of several selected positions;

FIGURE 19 is a detail longitudinal vertical sectional view, taken on the section line 19—19 of FIGURE 18 and looking in the direction of the arrows, showing the details of the latching device and its keeper according to FIGURE 18;

FIGURE 20 is a partial end elevational view, taken on the line 20—20 of FIGURE 17, and looking in the direction of the arrows, showing the relative locations of the slides on the carriage, which supports the drawing board, and the guides on the top of the desk, in the modification according to FIGURE 17;

FIGURE 21 is also a partial end elevational view, taken on the line 21—21 of FIGURE 16 and looking in the direction of the arrows, showing the relative locations of the slides on the carriage, and the guides, which are mounted on the top of the desk, in the modification according to FIGURE 16;

FIGURE 22 is a horizontal detail sectional view, taken on the section line 22—22 of FIGURE 20 and looking in the direction of the arrows, showing the relative locations of the slides on the carriage, which supports the drawing board, and the guides which are mounted on the top of the desk, in the modification according to FIGURE 16;

FIGURE 23 is a detail vertical sectional view, taken on the section line 23—23 of FIGURE 22 and looking in the direction of the arrows, also showing the details of the slides on the carriage, which supports the drawing board, and the guides which are mounted on the top of the desk;

FIGURE 24 is a fragmentary side elevational view of the carriage, which supports the drawing board, with certain parts shown in section, showing a modified arrangement of the slides on the carriage, which supports the drawing board, with respect to the winding rollers;

FIGURE 25 is a top plan view of the desk and the carriage, which supports the drawing board, with certain parts shown in section and showing a carriage elevating means;

FIGURE 26 is a side elevational view of the carriage, which supports the drawing board, and a sectional view of the desk, taken on the section line 26—26 of FIGURE 25 and looking in the direction of the arrows, and also showing the carriage elevating means;

FIGURE 27 is a substantially vertical sectional view, taken on the section line 27—27 of FIGURE 26 and looking in the direction of the arrows, showing the pivoted end of the elevating means and a detent for latching the carriage, which supports the drawing board, from sliding movement;

FIGURE 28 is a detail side elevational view showing the pivoted end of the carriage elevating means, and the detent for latching the carriage taken substantially along the line 28—28 of FIGURE 27 as viewed in the direction of the arrows;

FIGURE 29 is a detail transverse sectional view, taken on the section line 29—29 of FIGURE 25 and looking in the direction of the arrows, showing a modified arrangement of one of the cone clutches, which are positioned between the carriage supporting the drawing board and a slidible block arranged for travel along one of the parallel screws;

FIGURE 30 is a detail longitudinal sectional view, taken on the section line 30—30 of FIGURE 29 and looking in the direction of the arrows, showing the attachment of the cone clutch according to FIGURE 29 to the slide, which supports the drawing board, and the guide on the top of the desk;

FIGURE 31 is a detail horizontal sectional view, taken on the section line 31—31 of FIGURE 26 and looking in the direction of the arrows, showing a latch for holding the carriage, which supports the drawing board, against sliding movement along the desk top;

FIGURE 32 is a detail substantially vertical sectional view, taken on the section line 32—32 of FIGURE 28 and looking in the direction of the arrows, showing the hinge and hinge pin for tilting the carriage, which supports the drawing board;

FIGURE 33 is a detail partial transverse sectional view, taken on the section line 33—33 of FIGURE 25, and

looking in the direction of the arrows, showing the rear pivoted mounting for the carriage, which supports the drawing board;

FIGURE 34 is a side elevational view, similar to FIGURE 26, but showing the hinged carriage, which supports and elevates the drawing board, in the lowered position;

FIGURE 35 is a top plan view, taken on the section line 35—35 of FIGURE 34 and looking in the direction of the arrows, showing the mounting of the carriage, which supports the drawing board, for rotation about its vertical axis;

FIGURE 36 is a detail transverse sectional view, taken on the section line 36—36 of FIGURE 35 and looking in the direction of the arrows, showing the details of the mounting for the carriage, which supports the drawing board, for rotation about its vertical axis;

FIGURE 37 is a detail transverse sectional view, taken on the section line 37—37 of FIGURE 35 and looking in the direction of the arrows, showing the details of the slidable mounting for the carriage, which supports the drawing board, according to FIGURE 35;

FIGURE 38 is a detail transverse sectional view, taken on the section line 38—38 of FIGURE 35 and looking in the direction of the arrows, showing the locking means for securing the rotatable mounting of the carriage, which supports the drawing board in any selected position; and

FIGURE 39 is a schematic top plan view, showing that the carriage, which supports the drawing board, must first be pulled forward before it can be rotated about its vertical axis and into the desired angular position.

Referring now to the drawings in detail, and to FIGURES 1 and 2 in particular, the drawing board and the slidible carriage, which supports same, are here shown as mounted within the parallel sides and over an intermediate section of a desk. The lower section of the desk may be of any conventional construction. As shown, the lower section of the desk is comprised in part by front corner members 10, which are of angle bar shape. These corner members form legs (not shown) and are spaced apart longitudinally to provide an open space for the draftman's knees. An intermediate wall 11 is positioned parallel to the front corner members 10 and rear corner members 12 are also provided. These rear corner members 12 are likewise of angle bar construction and form legs (also not shown) at their bottoms. Side frame members 13 are provided across the tops of the front corner members 10 and across the tops of the rear corner members 12 for supporting the top. End walls 15 are provided and are secured over the corner members 10 and 12 and against the ends of the intermediate wall 11. A rear wall 16, similar to the end walls 15, is also provided and is positioned between the rear corner members 12.

Side frame members 14 are mounted on the tops of the front corner members 10—10 and rear corner members 12—12. A top is comprised in part by a solid plate 17, which is supported by the intermediate wall 11, the end walls 15 and the rear corner members 12—12. The end walls 15 are rabbeted into the top plate 17 at 17a as shown in FIG. 5. Between the end frame members 13—13 and between the intermediate wall 11 and the front side frame member 14, the top is open as shown in FIG. 3.

As shown in FIGURES 3, 4 and 5, a super structure is provided for partially enclosing the carriage, to be later described, at its sides. This super structure is comprised in part by sills 22—22, which are positioned on the top plate 17 and the end frame members 13—13. (See FIG. 2.) End walls 23—23 are vertically aligned with the end walls 15—15, respectively, of the main lower section of the desk and are rabbeted into the top plate 17 at 17b. Wings or side extensions 24—24 are mounted on the end walls 23—23 of the super structure, and the end walls 23—23 are rabbeted into the wings on the under sides of the latter at 24a.

The carriage is comprised in part by a bottom plate 30, which is slidable over the top plate 17 and the intermediate wall 11 on the main lower section of the desk. A rear plate 31 may be integrally formed with the bottom plate 30, or as a separate element and attached thereto in any suitable manner. This rear plate 31 has an inturned horizontal flange 31a at its top. Side plates 23 are positioned on the sills 22.

Bearing brackets 38 (see FIGS. 3 and 4) are positioned inwardly of the side plates 23. Along their tops these bearing brackets are formed with outwardly turned flanges 38a. At their front ends and adjacent their rear ends these bearing brackets are also formed with integral legs 38b, which in turn are formed at their bottoms with outwardly extending toe flanges 38c. The latter are secured to the bottom plate 30 of the carriage by bolts or machine screws 39. Also, at their rear ends the bearing brackets are formed with inturned right angle flanges 38d, the latter underlying the inturned flange 31a on the rear plate 31. These rear flanges 38d terminate in a downwardly and inwardly positioned web 38e, which latter is parallel to the rear plate 31.

The drawing board is shown at 40 and the paper trained thereover at 48. To secure the drawing board in place, screws 41 extend through suitable holes in the upper flanges 38a on the bearing brackets and into the drawing board.

The tensioning roller is shown in FIGURES 2, 3 and 5. This roller is rotatably mounted at the rear of the drawing board 40. This roller is comprised principally by a cylindrical tube 50. At each end of this tube 50 there are formed diametrically disposed recesses 51 in the side wall of the latter, which recesses are rectangular in cross section. Circular end plates 52 are received over the ends of the tube 50 and these end plates have diametrically positioned tongues 53 thereon, which are received in the recesses 51 in the ends of the tube. Stub shafts 54 are mounted centrally of the end plates 52 and these stub shafts are slidably mounted in slots (not shown) in the bearing brackets 38, which slots extend longitudinally of the brackets. Spacer collars 55 are positioned between the end plates 52 and the legs 38b. These may be two (2) part semi-cylindrical collars with a suitable central hole therein for receiving the stub shafts 54. The complementary halves of the semicylindrical collars are held together by either a split metal band 56, or by adhesive tape wrapped same. Beyond the legs 38b of the bearing brackets the stub shafts 54 pass freely through slidible blocks 58. These latter are held in place on the legs 38b of the bearing brackets by angle members 59 which have machine screws 60 securing their bottom flanges to the legs with their top flanges 59a holding the blocks 58 against the legs. Rods 61 are rotatably secured to the slidible blocks 58 and are received in suitable screw threaded holes 38c in the webs 38d on the bearing brackets. At their outer ends these rods 61 carry knobs 63, which knobs have hubs 63a rotatably received in suitable holes 36 in the rear plate 31 of the carriage. Coiled compression springs 62 surround the rods 61 and at one end abut the webs 38d on the bearing brackets and at their other ends the hubs 63a of the bearing brackets.

The rear winding roller is shown in FIGURE 8. It is comprised in part by a mandrel in the form of a hollow tube 65. An outer hollow cylinder 68, which may be of fiber, freely surrounds the mandrel 65. Collars 68 are received on the mandrel 65 and about the outer hollow cylinder 66 at its opposite ends. These collars 68 are held in position by radially positioned set screws 67. At each end of the mandrel there are formed diametrically disposed recesses 69, which recesses are rectangular in cross section. Circular end plates 70 are received over the opposite ends of the mandrel 65, and these end plates have diametrically disposed tongues 71 thereon, which are received in the recesses 69 in the ends of the mandrel. Axles 72 are positioned centrally of the end plates 70

and are received in inverted U-shaped notches 42 in the under sides of the bearing brackets 38. Coiled compression springs 73 surround the axles 72 and abut at one end the circular end plates 70 and at their other ends the bearing brackets 38. On one of the axles 72 there is mounted a hand wheel 74 for rotating the winding roller 66. For right hand operation this hand wheel will be on the right axle 72, as shown in FIGURE 4, and vice versa for left hand operation.

A releasable bearing support is provided for holding the axles 72 in place in the U-shaped slots 42 in the bearing brackets 38, as shown in FIGURE 8. These axles 72 are freely received in apertures 43 which extend through short levers 76, the apertures 43 extending along the transverse center line of the levers 76. The levers 76 are U-shaped in cross section and receive the lower sides of the bearing brackets 38, as shown in FIGURES 9 and 2. At one end the levers 76 are pivotally mounted on the bearing brackets 38 by short bolts 75, at their other ends they are formed with U-shaped slots 77 along their longitudinal center lines. Arms 80 have cam ends 80a, which are received in the U-shaped slots 77 in the levers and are pivotally mounted in the bearing brackets 38 by short bolts 79, which have wing nuts 81 on their outer ends. It will be apparent that upward movement of the arm 80, as viewed in FIGURE 2, will swing the lever 76 downward and thrust the axle 72 from the slot 42 in the bearing bracket 38 and that the rear winding rollers 65 and 66 may then be removed by disengaging the circular collar 70 and compression the spring 73 towards the bearing brackets 38; conversely, downward movement of the arm 80 will swing the lever 76 upward and securely latch the axle 72 in the slot 42 in the bearing bracket 38 to give sufficient thrust to prevent rotation of the rollers 65 and 66.

The front winding roller is shown at 82 (FIGURES 2, 3 and 4). This may be a fiber cylinder or a metal cylinder encased by a fiber sleeve. The latter construction is shown in FIGURE 24, which construction is substantially identical with the rear winding roller, previously described. As shown in the latter figure, the hollow metal cylinder 82 is a mandrel and is freely surrounded by a hollow outer cylinder 86, which may be of fiber. At each end of the mandrel 82 there are formed diametrically disposed recesses 83, which recesses are rectangular in cross section. Circular end plates 85 are received over the opposite ends of the hollow cylinder 82 and these end plates have diametrically disposed tongues 84 thereon, which are received in the recesses 83 in the ends of the mandrel 82. Collars (not shown) identical to collars 68 also surround the mandrel 82 and abut the outer hollow cylinder 86 at its opposite ends. These collars are similarly held in place by radially positioned set screws. Axles 89 are positioned centrally of the end plates 85 and are received in inverted U-shaped slots 42 in the under sides of the bearing brackets 38. On one of these axles 89 there is mounted a hand wheel 96 for the forward winding roller. Like the hand wheel 74 for the rear winding roller 66, this hand wheel is positioned on the right, as viewed in FIGURE 1, for right hand operation. The releasable bearing support for the front winding roller 86 is identical with that for the rear winding roller 66, as is the associated spring (not shown).

The drawing paper 48 is trained over the rear winding roller 66, the tension roller 50, the drawing board 40 and the front winding roller 86. It may be secured to the winding rollers 66 and 86 in any suitable manner, as by drafting tape or paper cement.

An elevating means is provided for raising the carriage 70 to an inclined position if desired, and without shifting same forwardly as shown in FIGURES 2 and 11. This means is comprised by a lifting bar 90 having a longitudinal slot 93 adjacent one end and an approximately right angle flange 90a at the other end. The flange 90a underlies the bottom plate 30 of the carriage at the rear

of the latter. A screw 94 having a lock nut 94a therein passes through the slot 93 and is received in an internally threaded cylinder 95, which latter is secured to the rear wall 16 of the lower sections of the desk. This elevating means may be positioned along the vertical center line of the rear wall 16 of the desk, or may be provided in duplicate and the cylinders 95 secured to the rear corner members 16. A levelling strip 18, of the same height as the thickness of the flange 99a on the arm is provided across the top of the desk, in vertical alignment with the intermediate wall 11.

In order to elevate the carriage through the elevating means just described, the carriage is shifted slightly rearwardly, until the front end of the bottom plate 30 is inside the front corner members 16-10. The carriage may then be tilted in the counter-clockwise direction, as viewed in FIGURE 2, and held in such position by setting the bar 90 in the selected position and clamping same by the screw 94.

FIGURE 6 shows an arrangement in which the carriage is supported for movement on a track and a clutch is provided for holding the carriage in any selected position. On each side of the carriage a channel member having a wall or web 96 is secured to the side plate 23 of the desk by bolts 97. The channel member has upper and lower flanges 96a and 96b, respectively, thereon, which are recessed at 99 adjacent their junctures with the web 96. An outer plate 100 travels in the upper and lower recesses 99 and an inner plate 104 over the faces of the flanges 96a and 96b. The plates 100 and 104 are held in assembled relationship by bolts 102 having nuts 103 thereon, which bolts pass through spaced holes adjacent the circumferences of the plates. An outer frusto-conical clutch member 106 has flanges at its opposite ends, which flanges also have arcuately spaced holes therein for receiving the bolts 102. An inner frusto-conical clutch member 107 has a cylindrical boss 107a on its outer face and an integral axially positioned shaft 108 on its inner face. The cylindrical boss 107a is slidably received in an axial hole 101 in the outer plate 100 to provide bearing support. The inner plate 104 also has an axial hole 105 therein and a flanged bushing 109 has its hub 109a received in this hole. Between the inner face of the inner clutch member 107 and the bushing 109, and surrounding the shaft 108, there is mounted a compression spring 110. The shaft 108 is threaded at its mid-section at 108a and reduced in diameter at its outer end at 108b.

The bottom plate 30 is here mounted in horizontal parallel relationship with the drawing board 40 by brackets 25 which have upper and lower flanges 25a and 25b, respectively, thereon. These flanges are secured to the bottom plate 30 and the drawing board 40 by screws 26. At their mid-section the brackets 25 have bosses 27 with axial bores therethrough in which the outer ends 108b of the shafts 108 are slidably received. The bores through the bosses 27 are each formed with a key way 28 in which a key 111 on the outer end of the shaft 108 is received to constrain the shaft against rotation. It will be apparent that the outer ends 108b of the shafts could as well be made square and complementary square holes formed through the bosses 27. A hand wheel 112 has a screw threaded bore through its hub by which it is rotatably mounted on the screw threaded mid-section 108a of the shaft 108. The hub of the hand wheel also has a circumferential groove 112a therein. An arcuate retainer plate 114 is secured by screws 113 to the boss 27 on the bracket 25 and has a flange 114a thereon which is received in the groove 112a in the hub of the hand wheel to constrain the latter against axial movement.

It will be apparent that the hand wheel 112 may be rotated in the counter-clockwise direction, as viewed from the left in FIGURE 6, to draw the inner clutch member 107 inwardly and compress the spring 110. The carriage may then be slid either forwardly or rearwardly, the outer

plate 110 travelling in the recesses 99 and the inner plate 104 travelling over the faces of the flanges 96a and 96b. When the carriage has reached the desired position, the hand wheel 112 may be rotated in the opposite direction 5 to move the inner clutch member 107 into engagement with the outer clutch member 106, the compression spring 110 being released and holding the clutch members in engagement.

The arrangement according to FIGURE 7 differs from 10 that according to FIGURE 6 in two features. The outer clutch member 106 is here replaced by a plurality, at least four (4) closed end cylinders 115, which are arcuately spaced around the inner plate 98a and the outer plate 103. These cylinders have aligned axially positioned holes 116 in their opposite ends, through which the bolts 102 pass. Within each cylinder 115 there is a plurality, preferably four (4) roller bearings 117, which surround the bolts 102. These roller bearings have conical or needle ends 117a, which are guided by the ends of 15 the cylinders 115. These cylinders rotate on the bolts 102 as axles and between the flanges 96a and 96b (see FIG. 6) of the channel or track member 96 and the outer clutch member 106. This arrangement has the advantage that the upper roller bearings 117 on the opposite sides 20 of the drawing board 40 prevent any twisting action by the clutches. If desired, separate plates (not shown) screwed to wings 24 and the sills of plate 30 may serve as tracks for the bearings. The outer conical clutch member 106 as shown in FIGURES 3 and 6 also has flanges at 25 its opposite ends for receiving bolts 102.

Another feature of the arrangement according to FIGURE 7 is that the outer ends 108b of the clutch shaft have separate mountings from the bearing brackets 38 which support the drawing board 40 and bottom plate 30. 30 Pedestals 118 have toe flanges 118b at their bottoms and are mounted on bottom plate 30 by cap bolts 119. At the tops of the pedestals 118 there are integral bosses 118a having axial bores therein in which the outer ends 108b of the clutch shaft are slidably mounted. The bottom plate 30 is wider than shown in the arrangement according to FIGURE 6 to provide space for the pedestals 118. This arrangement has the advantage that the bearing brackets 38 are separated from the pedestal mountings 118 for the carriage. The drawing board 40 and the 45 carriage may accordingly be removed and replaced without removing the pedestal 118, hand wheel 112 or the clutch 107.

In FIGURES 10 to 15, inclusive, there is shown a modification in which two (2) parallel screw threaded shafts 50 are provided for shifting the carriage transversely of the desk. As here shown the bottom plate 30 has a partial top plate 31a at the rear, which is on the same level as the wings 24-24. The channel members 96-96 are here mounted between the wings 24 and the sills 22.

The roller bearing mounting for the clutches is shown 55 in FIGURE 13. The inner plates 100 of the clutches in FIGURE 6 are here replaced by rectangular plates 120, which have inwardly offset extensions 120d of reduced width at their forward ends. The outer clutch member 106 of FIGURE 6 is here replaced by a clutch member 121 which is cylindrical on its outer surface. Cylinders 123 roll between the upper and lower flanges 96a and 96b of the channel members 96. These cylinders are rotatably mounted around the outer clutch members 121 by roller 60 bearings 122 which are similar to the roller bearings 117 of FIGURE 7. On the inwardly offset extension 120d of the plate 120 there are mounted roller bearings 125 on shafts 124. These roller bearings run respectively on the flanges 96a and 96b of the channel member 96. Their 65 purpose is to prevent rotation of the outer clutch member 121. Bolts 102 extend through outer clutch member 121, inner rectangular plates 120 and an outer plate (not shown) substantially identical to plate 104 (see FIG. 6) 70 form an integral unit.

As shown in FIGURE 12, the outer ends of the shafts

108b are here received in bores 127 in pedestals 128. The bores 127 have keyways 126 therein for the reception of the keys 111. At their bottom the pedestals 128 have out-turned flanges 128a. The flanges 128a rest on slides 130 and are secured to the latter by bolts 131. These slides 130 are slidably received under the flanges 132a of guide members 132. The latter are secured by screws 133 to the bottom plate 30 of the superstructure.

The pedestals 128 have screw threaded bores 129 therein in which are received elongated screw threaded shafts 135. As shown in FIGURES 11 and 14 these shafts are reduced in diameter at their outer ends at 135a and are rotatably mounted in brackets 136—136 at the opposite sides of the bottom plate 30 of the carriage. The brackets 136—136 have right angle bottom flanges 136a by which they are secured to the bottom plate 30 of the carriage by screws 137, which pass through the guides 132. As thus mounted, the brackets 136—136 thrust the clutch to the top of the desk. Collars 140 are secured on the reduced ends 135a of the shafts by radially positioned set screws 139 and these collars abut the brackets 136—136 to hold the shafts against longitudinal movement. By shifting the positions of the clutches 125 relative to the bottom plate 30, the drawing board 40 as shown in FIG. 11 may be elevated to a desired angle or vertical position to suit the draftsman.

The two shafts 135—135 are interconnected by a chain 144, (see FIG. 10) which runs over chain gears 142—142 on the inner ends of the shafts. These chain gears are held in place by vertically positioned set screws 143 through their hubs 142a. At their outer ends the shafts 135 are formed in square sections 135b. A hub crank 145 may be placed on either end of either shaft 135 for rotating the latter and moving the carriage transversely of the desk. The rear plate 31 has a hole 32 therein for receiving the thumb of the hand crank 134a.

The brackets 136—136 for the screw threaded shafts 135—135 are mounted above and in parallel relation to the guide 132, as in the arrangement according to FIGURE 11.

As shown in FIG. 11 the axles 72 of the tensioning roller 50 are held in place by U-shaped slots in the bearing bracket 38, short levers 76 and arm 80 as disclosed previously in FIGURES 8 and 9.

In the species of FIGURE 16 there is shown an arrangement which is particularly adaptable to a square drawing board. In this arrangement the slides 130 are secured directly to the toe flanges 38c on the bearing brackets 38 of the carriage and the guide 133 is secured directly to the bottom plate of the carriage by screws 152.

As shown in phantom lines the carriage can be pulled forwardly over the bottom plate 20 and beyond the stationary desk top 17. In such position the carriage is conveniently located for removal or replacement of the winding rollers 66 and 82 and the tensioning roller 50. Also, in such position the draftsman can conveniently draw from either side board, as well as from the front.

The arrangement shown in FIGURES 17 and 20 is also particularly adaptable to a square drawing board 40 mounted in bearing brackets 38 and toe flanges 38c. In this arrangement the carriage is also provided with slides 130 along its longitudinal center lines. Only two guides 136 are used as before. With this arrangement the carriage may be removed from the desk top 17, over the bottom plate 20, rotated through 90 degrees and then replaced on the desk top. The carriage is shifted from one position to another by pulling it forward, turning through 90 degrees and then pushing it rearwardly to the full line position as shown. The drawing board 40 may then be positioned as the draftsman may like and to suit principally the length of the drawing. It is of course easier to work a long drawing from the sides but there are exceptions and the present arrangement provides as well for working a long drawing from the ends, if desired.

The arrangement shown in FIGURE 18 is distinguished from those already described by several features. The bearing brackets 38 of the carriage has four (4) notches 42 therein for its axles 54, 72 and 89 of the winding rollers 66 and 82 and the tensioning roller 50 formed in pairs with the notches of end pair uniformly spaced and the pairs uniformly spaced from the ends of the carriage. With this arrangement both winding rollers 66 and 82 may be placed near the front of the carriage and the tensioning roller 50 near the rear of the carriage, as shown, or vice versa.

According to the construction of the desk here shown, the super structure is complete between the wings 24—24. The latter includes a bottom plate 20, which rests on the top plate 17 of the desk. There is also a rear plate 31, which is aligned with the rear wall 10 of the desk. Corner rods 35 are secured to the bottom plate 20 and the rear plate 31 by bolts or pins 34. The guides 133 are secured to the bottom 20 by screws 152, as shown in FIG. 19.

20 A latch 154 is provided for holding the carriage in any one of several selected positions along the guides 133—133, as may be desired. This latch is shown in position on the carriage and the super structure of the desk in FIGURE 18 and in detail in FIGURE 19. An angle bar 148 is secured to the top of one of the slides 130 by bolts 149. This angle bar has longitudinally aligned holes 150 in its upstanding flange. A right angle bracket 32a is secured to the bottom plate 20 of the super structure by screws 153. This bracket has a hole in its upstanding flange adapted to align with the holes 150 on the upstanding flange of the angle bar 148. An L-shaped pin 154 is inserted in the aligned holes 150 in the upstanding flanges of the angle bar and the bracket. As shown in FIGURE 18, the holes 150 in the upstanding flange of the angle bar 148 may be replaced by, or supplemented with holes 151 in the toe flanges 38c of the bearing brackets 38, if desired.

The angle bar 148 is attached between the toe flanges 38c to the slides 130 by rivets 149 (see FIGURE 19).

40 In FIGURE 24 there is shown an arrangement in which the slides 132 are mounted transversely of the carriage. They are secured to the latter by bolts 155 which extend through suitable holes in the toe flanges 38a on the bearing brackets 38 and have nuts 156 therein. This arrangement is particularly adapted to the carriage where the latter is made square in top plan view. In such case, the slides 132 may also be mounted longitudinally of the carriage, using the same holes in the toe flanges 38a and the same bolts 155. This latter position of the slides 132 is shown in phantom lines in the same figure. The advantage of this arrangement is in the making of a drawing that is the same or a lesser length than the rollers, instead of making a drawing on a long sheet of paper wound on the rollers and turning the board through 90 degrees. In this case the views on the two drawings will have the same relative positions. However, the rear winding and tension rolls may be added and supported in the U slots in the bearing bracket 38.

60 In FIGURES 25, 26, 27, 28, 32 and 33 there is shown an arrangement for tilting the carriage and drawing board, which is alternative to or combined with the tilting means shown in FIGURE 3. The guides 132—132 are mounted on a hinge plate 157 beneath the carriage, as shown in FIGURES 27, 28 and 32. At the inner end of this plate 157 there is secured by a rivet 158 a hinge 159 having a pivot pin 160. The complementary leaf of this hinge is in the form of an elongated plate 162 which is secured to the bottom 20 of the central section of the super structure by screws 161. At the opposite of the plate 162, adjacent the rear wall of the super structure, this plate is formed with a loop 163. (See FIGURE 26.) A rod 164 has a right angled, lower end, which is pivotally secured in the loop 163. At the outer end of the guide 132 there is mounted an offset bracket 165,

and one arm of this bracket being secured to guide 132 and the other arm having a hole therein for receiving the main body of the rod 164. A screw threaded hole is formed in this latter arm at right angles to the hole which receives the rod 164. A set screw 166 is received in the screw threaded hole in the arm of the bracket 163 and has a knob 167 on its outer end (see FIGURE 25).

As best seen in FIGURE 27, the angle bracket 168 of the latch 154, which is similar to the arrangement disclosed at 32a (FIGURE 19) is secured to the bottom 20 of the super structure, is replaced by an angle bracket 168 which has a right angle flange 163a at its bottom and a boss 168b at its top. The flange 163a is received under the guide 132 with the hinge plate 157 and held in place by the screws or rivets 158. The boss 168b has a hole therethrough, which is adapted to relatively align with the holes 151 in the toe flanges 38c of the bearing brackets 38 and angle iron 148 to receive the L-shaped pin 154. The angle irons 148 support the toe flanges 38c of the bearing bracket 38.

In the arrangement according to FIGURE 33, the loop 169 at the rear end of the elongated plate 162, as shown in FIG. 26, is replaced by a second hinge loop 171 having a pivot pin 170 therein. The central butt of the hinge comprises a plate 171b in which latter there are formed holes at right angles for riveting to the rod 164. One hole diametrically positioned in a boss 171a receives the depending rod 164. The other hole is axially positioned in the boss and receives a beaded set screw 172.

With the carriage and drawing board held in the elevated position by the hinge 159 and rod 164, as shown in FIGURE 26, the carriage may be pulled outwardly without disturbing such positions. In addition to the features of elevating the drawing board, the carriage can be elevated and held in position by the clutches 176. Also, the carriage and drawing board may be pulled forward, as in the previous modifications, with or without elevating the carriage, as indicated in dotted lines in FIG. 26.

In FIGURE 26 there is also shown an alternative manner of training the paper 48 over the front and rear winding rollers 66 and 82, respectively, and the forward tensioning roller 58 as shown, the paper 48 is trained under the forward winding roller 66, over the rear winding roller 82, and under the forward tensioning roller 58, and over the drawing board 40 and wound on roller 82. This manner of training the paper over the rollers keeps the paper taut at all times and prevents excessive slack when either of the winding rollers are turned. It should be noted that, if the paper is kept taut at all times, the shifting of same sideways will be practically eliminated.

In FIGURES 29 and 30, there is shown still another alternative form of the clutch and this clutch is used in the arrangement according to FIGURE 6. Guides 174 are mounted on the sills 22 of the super structure by screws 173. These guides are similar to the guides 132 fastened to the bottom 20 of the super structure. By screws 173 slides 175 are slidably mounted in the guides 174. An outer clutch member 176, having flanges at both ends and a frusto-conical inner surface, is secured to each slide 175 by bolts 177 at toe flanges 176a. An inner frusto-conical clutch member 178 is received within the outer clutch member 176. Inner and outer plates 180 and 182, respectively, are secured over the outer clutch member 176 and held in place by bolts 189a, which extend through aligned holes 180 in the plates and the flanges of the outer clutch member 176. The inner clutch member 178 has on its face a guiding boss 178a, which slides and is received in a central hole 183 in the outer plate 182. On its other face the inner clutch member has an integral centrally positioned shaft 178b, which slides and is received in a central hole 181 in the inner plate 180. A coiled compression spring 185 is positioned between the inner clutch member 173 and the outer plate 182, surrounding the guide 178a.

Pedestals 186 which are similar to the pedestals in FIGURE 12 have outwardly extending flanges 186a at their bottom. These pedestals 186 are secured by bolts 130 which extend through aligned holes in the flanges 186a and the slides 132a. The pedestals 186 have transversely extending screw threaded bores therein, which receive the screw threaded shafts 135. Each pedestal has an axially extending bore 187 therein and a keyway along their bore. A key 188 is secured in a complementary keyway in central shaft 178b of the inner clutch member and constraining the latter against rotation. A plate 190 having a central hole therein is secured over the outer face of each pedestal by machine screws 189. In the plate there is rotatably mounted a shaft 192, which 5 has an inner screw threaded end 179a received in an axially positioned screw threaded bore 192 in the central shaft 178b on the inner clutch member. The shaft 192 also has an integral disc 193 therein, which is positioned in an counterbore 187a in the pedestal and abuts the plate 10 190 on the inner surface of the latter. A handwheel 195 is secured in the outer end of its shaft 192 by a key 196, in a keyway 196a.

In the type of cone clutch here described the disc 193 rotating in the counterbore 187a in the pedestal takes up 15 the thrust load on the clutch. This thrust load is opposite to that on the clutch described in connection with FIGURE 6, and places the bottom plate 20 of the carriage in compression, while the thrust load of the clutch of FIG. 29 places the bottom plate 20 in tension thereby 20 tending to force the edge 1b of the sill 22 against the edge 1a of the bottom plate 20 as assistance in preventing rotation and holding the carriage in place as shown in FIG. 3.

In FIGURE 31 there is shown a latch for holding 25 the central section of the super structure in place. As shown by the arrow in FIGURE 26 this central section can be tilted upwardly above the clutches 176—176 or by pivots 139. At one corner of an end strip 21, which is on the front of the bottom plate 20 of the central 30 section of the super structure, there is formed a right angled recess 200 by a large diameter bore, which extends longitudinally of the bottom 20, and a smaller diameter bore, which extends transversely of the bottom and intersects the first bore. A keeper in the form of a bushing 45 201 is mounted in a bore in either the adjacent front corner member 10 or the inner end wall 15 of the desk. The movable element of the latch (see FIGURE 19) is a detent in the form of a right angled pin 204, which has one arm in the lengthwise extending bore and the other arm in the transversely extending bore. A collar 202 is force fitted on the latter arm and this collar is 50 slidably mounted in a bushing 203, which is force fitted in the transversely extending bore. It will be obvious that the pin 204 may be pulled transversely of the bottom 55 20 in recess 200 to clear the adjacent end wall 15, the central sections of the super structure may be swung upwardly, in the direction indicated by the arrow in FIGURE 26, employing the clutches 176—176 as pivots and the pin pushed outwardly to engage in the bushing 60 201 and hold the bottom 20 of the super structure in the elevated position. The keepers 201 may be provided at spaced locations along the end walls 15, or the front corner members 10, to hold the central section of the 65 super structure in any one of several elevated positions, as may be desired. Also, the latch may be provided on both sides of the bottom 20 of the central sections of the super structure to make the central section more stable in any one of the elevated positions.

In FIGURES 34, 35, 36, 37 and 38 there is shown 70 an arrangement in which a circular drawing board is rotatable on the carriage. The clutches, slides and guides, hinges and latch are the same as in the arrangements according to FIGURES 25, 26, 27 and 28. As shown in FIGURE 35, the carriage is supported by two inverted 75 L-shaped longitudinally extending bars 205—205, which

have right angle extensions 205a at their outer ends. In FIGURES 36 and 37 it will be seen that these bars have outer flanges 205b, which flanges are cut away across the right angle extensions 205a to leave extensions 205d of the horizontal flanges. These extensions are secured to the slides 130 by bolts 131 having suitable nuts therein, which bolts are received in aligned holes in the extensions and the slides, the L-shaped bars 168 being secured to the slides 130.

A double walled annular plate 206, which is channel shaped around its circumference to form upper and lower flanges 206a and 206b, respectively, and which may consist of two half sections 206e and 206f and is rotatably mounted on the longitudinally extending bars 205—205 and the L-shaped bars 168 as shown in FIG. 36. This plate is constrained in its circle of rotation by stud bolts 207, only one of these being shown but three or four being preferably provided. These stud bolts 207 are received in screw threaded holes in the top flanges of the bars 205, have nuts 208 therein and washers 209 beneath the nuts. The washers 209 grip the outer edge of the lower flange 206b on the annular plate 206, which rests on the supporting bars 205—205 and L bars 168—168.

As shown in FIGURE 35 one set of the stud bolts 207 and washers 208 is here replaced with a cam 213a, are provided on the rear longitudinal bar 205 and to the right of the transverse center line. Other sets will preferably be provided on both the front and rear longitudinally extending bars 205—205 and symmetrically positioned on the opposite sides of the transverse center line to constrain the annular plate.

In the alternative arrangement according to FIGURES 34 to 37 the front and rear longitudinally extending bars 205—205 may be replaced by a square supporting plate 210, which has a downwardly extending flange 210a and an upwardly extending flange 210b similar to the L bars 168, the plate 210 being above and secured to the slides 130. With this arrangement the annular plate 206 is entirely supported in its circle of rotation by the plate 210 and constrained by the stud bolts 207, nuts 208, and washers 209.

The plate 210 may also have an inside upwardly extending circular flange 213 to match the inside diameter of the annular plate 206. This circular flange 213 also constrains the annular plate in its circle of rotation with assistance of bolts 207, nuts 208 and washers 209.

Rectangular plates 212, which have one corner cut away, are secured by bolts or rivets 211 to the upper flange 206a of the rotatable annular plate 206. There are preferably four (4) of these annular plates, spaced 90 degrees apart. The toe flanges 38 on the bearing brackets 38 of the carriage are secured to these brackets by the bolts or machine screws 39.

In order to lock the rotatable annular plate 206 and the carriage therein in the selected position, an arrangement is provided, as shown in FIGURE 35. The fourth bolt, nut and washer set 207—208—209, which would be positioned on the front longitudinally extending bar 205, on the right of the transverse center line as shown in this figure and in transverse alignment with the set shown, is here omitted and is replaced by a manually operated cam 213a. This feature is shown in detail in FIGURE 38. The cam 213a has a handle 213 therein and is rotatably mounted on a stud bolt 207 having a nut 208 thereon. This stud bolt is received in a screw threaded hole in the top flange of the front longitudinally extending bar 205 and the cam is arranged to engage with the lower flange 206b on the rotatable annular plate 206 to hold the latter in the selected position. Additional cams 213a could be applied to constrain the annular plate 206 or be substituted for any or all of washers 209 and nuts 208, if desired.

As shown in phantom lines in FIGURE 34 it is necessary to pull the carriage and board 40 forward before rotating same, so that they will clear the clutch housings

176—176 (see FIG. 35) while being rotated through 90 degrees. In FIGURE 39 the carriage and board are shown in top plan view in the forward position before being rotated, in phantom lines. After the carriage and board have been pulled forward and rotated through 90 degrees, as shown in full lines, they may be kept in that position for convenience in drafting, or pushed rearwardly to position over the bottom plate 30 above the top 17 of the desk.

10 The various slides, guides, tracks, channels and other components as herein shown and described do not necessarily limit these particular designs of these parts to this invention for shifting the drawing board.

Having now fully described my invention, which I claim as new and useful and desire to secure by Letters Patent of the United States, from the foregoing it will now be seen that there is herein provided an improved rotatable and translatable drawing board construction which accomplishes all of the objects of the invention and others including many advantages of great practical utility and commercial importance.

As many embodiments may be made of this inventive concept, and as many modifications may be made in the embodiments hereinbefore shown and described, it is to be understood that all matter herein is to be interpreted merely as illustrative, and not in a limiting sense.

I claim:

1. A drawing board mounting comprised by a carriage arranged to travel over a horizontal surface, a drawing board supported on said carriage, an arrangement of rollers over which the drawing paper is trained comprised by a winding roller along one edge of the drawing board, a tension roller along the opposite edge of the drawing board, a second winding roller intermediate the first winding roller and the tension roller, parallel tread members on the opposite sides of said carriage, and supports including parallel plates slidable along the opposite edges of said parallel tread members and rollers carried by said plates and engaging said parallel tread members.

2. A drawing board mounting comprised by a carriage arranged to travel over a horizontal surface, a drawing board supported on said carriage, an arrangement of rollers over which the drawing paper is trained comprised by a winding roller along one edge of the drawing board, a tension roller along the opposite edge of the drawing board, a second winding roller intermediate the first winding roller and the tension roller, parallel tread members positioned on the opposite sides of said carriage, supports including parallel plates slidable along the opposite edges of said parallel tread members, stub shafts positioned axially of said parallel plates, rollers carried by said plates and engaging said parallel tread members, and clutches intermediate said plates and the respective stub shafts.

3. A drawing board mounting comprised by a carriage arranged to travel over a supporting structure, a drawing board supported on said carriage, an arrangement of rollers over which the drawing paper is trained comprised by a winding roller along one edge of the drawing board, a tension roller along the opposite edge of the drawing board, a second winding roller intermediate the first winding roller and the tension roller, stub shafts on the opposite sides of said carriage, parallel tread members mounted on the supporting structure and positioned on the opposite sides of said carriage, supports including parallel plates on the opposite sides of said parallel tread members and having aligned holes therein receiving said stub shafts, rollers carried by said plates and engaging said parallel tread members, and clutches intermediate said plates and the respective stub shafts.

4. A drawing board mounting comprised by a carriage arranged to travel over a supporting structure, parallel guides mounted on the carriage, a drawing board supported on said carriage, an arrangement of rollers over which the drawing paper is trained comprised by a wind-

ing roller along one edge of the drawing board, a tension roller along the opposite edge of the drawing board, a second winding roller intermediate the first winding roller and the tension roller, stub shafts on the opposite sides of said carriage, slides movable in said parallel guides, pedestals secured to said slides and having bores therien for receiving the stub shafts on the carriage and threaded holes therein, and screw threaded shafts received in the screw threaded holes in the pedestals for moving the pedestals and the slides along the guides.

5. A drawing board mounting comprised by a carriage arranged to travel over a supporting structure, parallel guides mounted on the carriage, a drawing board supported on said carriage, an arrangement of rollers over which the drawing paper is trained comprised by a winding roller along one edge of the drawing board, a tension roller along the opposite edge of the drawing board, a second winding roller intermediate the first winding roller and the tension roller, stub shafts mounted on the opposite sides of said carriage, slides movable in said parallel guides on the opposite sides of said carriage, pedestals secured to said slides and having bores therein for receiving the stub shafts on the carriage and threaded holes therein, screw threaded shafts received in the screw threaded holes in the pedestals for moving the pedestals and the slides along the guides, chain sprockets mounted on said screw threaded shafts and a chain trained over said chain sprockets for conjoint operation of said screw threaded shafts.

6. A drawing board mounting comprised by a carriage arranged to travel over a supporting structure, a drawing board supported by said carriage, an arrangement of rollers over which the drawing paper is trained comprised by a winding roller along one edge of the drawing board, a tension roller along one edge of the drawing board, a second winding roller intermediate the first winding roller and the tension roller, parallel tread members mounted on the supporting structure and positioned on the opposite sides of the carriage, stub shafts positioned on the opposite sides of the carriage, parallel guides mounted on the opposite sides of the carriage, slides movable in said parallel guides, pedestals secured to said slides and having bores therein for receiving the stub shafts on the carriage, cone clutches comprised by frusto-conical members on said stub shafts and complementary frusto-conical members surrounding said first frusto-conical members, outer frusto-conical members surrounding said complementary frusto-conical members and arranged to run on the respective tread members, and rollers bearings between said outer frusto-conical members and said complementary clutch members.

7. A drawing board mounting comprised by a carriage arranged to travel over a supporting structure, a drawing board supported by said carriage, an arrangement of rollers over which the drawing paper is trained comprised by a winding roller along one edge of the drawing board, a tension roller along one edge of the drawing board, a second winding roller intermediate the first winding roller and the tension roller, parallel tread members mounted on the supporting structure and positioned on the opposite sides of the carriage supports including first plates having holes therein adapted to run along one side of said parallel tread members and second parallel plates having aligned holes therein adapted to run along the other side of said parallel tread members, parallel guides mounted on the opposite sides of the carriage, slides movable in the parallel guides, pedestals secured to said slides and having bores therein for receiving the stub shafts on

the carriage, cone clutches comprised by frusto-conical members on said stub shafts, and complementary frusto-conical members surrounding said first frusto-conical members and received in the holes in said parallel plates, outer frusto-conical members surrounding said complementary frusto-conical members and arranged to run on the respective parallel tread members, and roller bearings between said outer frusto-conical members and said complementary clutch members.

10. A drawing board mounting comprised by a carriage arranged to travel over a supporting structure, a drawing board supported by said carriage, an arrangement of rollers over which the drawing paper is trained comprised by a winding roller along one edge of the drawing board, a tension roller along one edge of the drawing board, a second winding roller intermediate the first winding roller and the tension roller, parallel tread members mounted on the supporting structure and positioned on the opposite sides of the carriage, supports including first plates having holes therein adapted to run along one side of the parallel tread members and second parallel plates having aligned holes therein adapted to run along the other side of said parallel tread members, ball bearings mounted between said parallel plates and arranged to run on the respective parallel tread members, parallel guides mounted on the opposite sides of the carriage, slides movable in the parallel guides, pedestals secured to said slides and having bores therein for receiving the stub shafts on the carriage, cone clutches comprised by frusto-conical members on said stub shafts and complementary frusto-conical members surrounding said first frusto-conical members and received in the holes in said parallel plates, outer frusto-conical members surrounding said complementary frusto-conical members and arranged to run on the respective parallel tread members, and roller bearings between said outer-frusto-conical members and said complementary clutch members.

15. A mounting for supporting a drawing board between parallel surfaces comprised by channel members mounted on said parallel surfaces, plates slidably mounted in said channel members, shafts mounted on said plates, a carriage supporting the drawing board, parallel tracks mounted on the bottom of said carriage, slides movable through the tracks, pedestals mounted on said slides and receiving said shafts, latch means for securing said carriage in a selected position of adjustment, said latch means comprising an angle bar, an angle bar having openings therein on one of its slides, a bracket having an opening therein carried by said bottom of said carriage, and an L-shaped pin extending through said opening in said bracket and a selected one of said openings in said angle bar.
